GIRDLE

Jack E. Robbins, New York, N. Y.

Application July 9, 1956, Serial No. 42,186

Term of patent 14 years

(Cl. D20—2)

Figure 1 is a front elevational view of a girdle showing my new design, and

Figure 2 is a rear elevational view of the girdle shown in Figure 1.

I claim:

The ornamental design for a girdle, as shown.
